UNITED STATES PATENT OFFICE.

ELWOOD CAREY, OF MYRTLE POINT, OREGON.

ROPE-CLAMP.

No. 881,662.

Specification of Letters Patent.

Patented March 10, 1908.

Application filed August 31, 1907. Serial No. 390,973.

To all whom it may concern:

Be it known that I, ELWOOD CAREY, a citizen of the United States, residing at Myrtle Point, in the county of Coos and State of Oregon, have invented a new and useful 5 Rope-Clamp, of which the following is a specification.

This invention has relation to rope clamps and it consists in the novel construction and 10 arrangement of its parts as hereinafter shown and described.

The object of the invention is to provide a clamp adapted to be used upon hammock and tent guy ropes and which is so constructed 15 as to be easily and readily shifted along the rope and which will positively engage and grip the rope after it has been adjusted.

The clamp consists of the jaw member having an eye at one end and a hooked portion at its opposite end. A member is pivoted 20 to the first said member and constitutes the other jaw member of the clamp. The pivoted jaw member is adapted to swing in a parallel plane only with relation to the first said jaw member. A pin is adapted to pass transversely through the pivoted member and secure the same to the supporting jaw member and the pivoted member is provided 25 with a notch for the reception of the rope and with a notch for the reception of the extremity 30 of the hooked end of the supporting jaw member.

In the accompanying drawing:—Figure 1 is a plan view of the clamp applied to a rope. 35 Fig. 2 is a horizontal sectional view of the clamp, and Fig. 3 is a side elevation of the clamp.

The clamp consists of the supporting jaw member 1 which is provided at one end with 40 an eye 2 and at its opposite end with a hooked portion 3. The member 4 is pivoted to the member 1, as at 5, and is limited to swing in a parallel plane only to either side of the member 1. The cross pin 6 may be 45 passed transversely through registering perforations in the members 4 and 1, whereby, the member 4 is fixed with relation to the

member 1. The member 4 is provided at its end with a rope receiving notch 7 and at its upper edge with a notch 8 adapted to receive 50 the extremity of the hooked portion 3 of the member 1.

In operation, one end of the rope is attached to the eye 2 of the member 1 and the hooked portion 3 of the member 1 is passed 55 around the rope at the point thereof desired to be clamped. The member 4 is then swung laterally on the pivot 5 and the notch 7 thereof receives the side of the rope and impales the same against the inner surface of the 60 hooked portion 3 of the member 1. At the same time, the notch 8 receives the extremity of the portion 3 and braces the same against strain. When the parts are thus applied to the rope the pin 6 is inserted in the 65 registering perforations of the members 4 and 1, when the member 4 is restrained from movement relative to the member 1.

While the herein described device has been referred to as designed for use upon hammock and tent guy ropes it is to be understood that it can also be used as a "choker" hook in logging on steep ground. These devices are used in this art for the purpose of preventing the logs becoming loose within 75 the cable.

Having described my invention what I claim as new and desire to secure by Letters-Patent is:—

A clamp comprising a supporting member 80 having a hooked portion, a member pivotally mounted upon the supporting member and having a notched end adapted to lie within the hooked portion of the supporting member and being provided with a notch for the 85 reception of the extremity of the hooked portion.

In testimony that I claim the foregoing as my own, I have hereto affixed my signature in the presence of two witnesses.

ELWOOD CAREY.
